(57) **CLAIM**

The ornamental design for a “holder for portable electronic device,” as shown and described.

DESCRIPTION

FIG. 1 is a perspective view of a holder for portable electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view viewed from another visual angle thereof;

FIG. 9 is a perspective view thereof, showing the holder for portable electronic device in a state of use for clarity of disclosure;

FIG. 10 is another perspective view thereof;

FIG. 11 is another perspective view thereof, showing the holder for portable electronic device in an alternate state of use for clarity of disclosure;

FIG. 12 is left side view thereof, showing the holder for portable electronic device in a state of use with an object for clarity of disclosure; and,

FIG. 13 is another perspective view thereof.

The broken lines in the drawings depict environmental subject matter that forms no part of the claimed design.
